UNITED STATES PATENT OFFICE.

MARK MASON CONDRON, OF MARSHFIELD, OREGON.

COW-MILKING MACHINE.

SPECIFICATION forming part of Letters Patent No. 655,200, dated August 7, 1900.

Application filed April 3, 1900. Serial No. 11,368. (No model.)

To all whom it may concern:

Be it known that I, MARK MASON CONDRON, a citizen of the United States, residing at Marshfield, in the county of Coos and State 5 of Oregon, have invented a new and useful Cow-Milking Machine, of which the following is a specification.

This invention relates to a cow-milking apparatus or machine wherein a suction or vacuum is established to cause the milk to be drawn from the cow's teats; and the object of the improved construction is to provide a simple, cheap, and easily-operated apparatus for milking one or more cows thoroughly and 15 rapidly without annoyance or injury to the animals; also, with a more natural and less forceful operation, and also to have means for automatically regulating the pressure or suction force and to utilize the prime generator 20 of the latter by a simple adjustment of the parts for thoroughly cleansing the apparatus by the use of water, and thereby always maintaining the same in a pure and sweet condition and ready for immediate use.

25 The invention consists in the construction and arrangement of the several parts, which will be more fully hereinafter described and claimed.

In the drawings, Figure 1 is a perspective 30 view of a stanchion, showing a cow in position therein and a portion of the improved apparatus operatively applied. Fig. 2 is a longitudinal vertical section of the suction or vacuum creating cylinder and parts intimately connected thereto, together with operating means therefor. Fig. 3 is a transverse vertical section of a receiver forming a part of the improved apparatus. Fig. 4 is a sectional elevation of one of the valve connections. Fig. 5 is a detail perspective view 40 of a gravitating valve located in the receiver. Fig. 6 is a detail view of a clamp employed for securing the parts of the receiver. Fig. 7 is a detail view, broken away in part, showing the teat-cup cover. Fig. 8 is a detail view 45 of one of the plug-valves.

Similar numerals of reference are employed to indicate corresponding parts in the several views.

50 The numeral 1 designates a suction-cylinder preferably formed with laterally-projecting securing-flanges 2 for securement to a

base 3, disposed in any suitable position within a cow stable or shed or elsewhere, as may be desired. The said cylinder 1 has a front 55 closed end 4 and a rear open extremity 5, and therein is movably mounted a piston 6, to which a piston-rod 7 is attached and runs rearwardly to a crank-arm 8, secured to a shaft 9, the latter being supplied with a driving-pulley 10, which is intended to be engaged by a belt from any suitable driving source.

It will be understood that the piston 6 will be equipped with a suitable packing for an 65 obvious reason, and connected to the lower front portion 4 of the cylinder is a suction-pipe 11, having a particular form of compound plug-valve or faucet 12 seated therein adjacent the cylinder. The said plug-valve or 70 faucet comprises the ordinary form of plug, so far as shape is concerned, and having extending therethrough in one direction an upwardly-curved way 13, and in a plane at right angles said valve has a straight way 14, extending therethrough and leading to a check-valve 15, normally located in a recess or seat 16, so as to avoid interfering with the rotation of the plug in changing it from one position to another to accommodate different 75 operations, as will be hereinafter explained. The way 13 is upwardly curved to extend over the plane of the way 14 below the same and is without obstruction, and to operate the plug and turn it from one position to the 80 other a suitable handle or grip 17 is attached to the upper portion thereof. The suction-pipe 11 extends through the line of stanchions or stalls, as the case may be, and at regular intervals is supplied with stop-cocks 18 to 90 shut off portions of the apparatus and arrange for the operation of the same with one or more cows, and adjacent to said stop-cock T-couplings 19 or analogous connections are situated in the said suction-pipe, and to each a flexible suction-conveyer 20 is attached and runs to an elbow 21, secured to the top central portion of a receiver 22 of the form shown and provided with a surrounding horizontally-disposed central flange 23, to opposite portions of which a supporting-strap or analogous device 24 is loosely and separably connected by chains or the like, as at 25, and by means of the said strap each receiver is supported in 95 100

proper position on the cow to be milked. Each receiver also has four upstanding nipples 26, arranged concentrically on the upper part with relation to the elbow 21, and connected thereto are rubber or other flexible teat-cups 27, which are interiorly shaped to snugly receive the teats of a cow.

To the lower central portion of the receiver 22 an outlet-elbow 28 is attached, and in the upper part thereof and the adjacent bottom portion of said receiver a valve-seat 29 is constructed for co-operation with a gravitating valve 30 of the form clearly shown by Fig. 5 and having an upwardly-projecting stem 31, terminating in upward-divergent arms 32, which prevent the said valve from lowering or falling beyond a predetermined distance. The said valve operates as a check to communication between the receiver and the outflow-elbow 28 while the suction or vacuum force is being exerted upon the receiver, and at the time the milk is drawn from the teats of the cow and when the said suction or vacuum force is relieved and it is desired to have the milk flow out from the receiver the said valve is free to fall and open communication between the outflow-elbow 28 and the receiver 22, and from said elbow the milk is conveyed by means of a flexible conduit or pipe 33, running to a general conveyer 34, disposed in a stable or shed adjacent the suction-pipe 11 and having a terminal spout or outlet attachment 35, adapted to be connected to a can or other receptacle 36, as shown by Fig. 1. The outflow-elbow 28 is also supplied with a vent 37, which permits the ingress of air to the said elbow and facilitates the outflow of the milk by breaking up the counteracting effect of the suction or vacuum force that may still be present to a more or less degree. The teat-cups 27, conveyer 20, and conduit 33 are all attached to the parts of the receiver with which they connect by a ring-clamp 38, as shown by Fig. 6, it being understood that the several parts are of a flexible nature, and the binding action of the said clamp will in each instance set up a thoroughly air-tight connection and also affords means of easily connecting or disconnecting said parts. The front closed end 4 of the cylinder 1 also has a regulator connected thereto and composed of a pipe 38^a, having a frusto-conical seat 39 in the upper portion thereof adjacent the end 4 of the cylinder and in which an inwardly-opening similarly-shaped valve 40 is mounted and connected by a link 41 to the short end or section of a lever 42, supported in a fulcrum 43, secured to said pipe 38^a and having an adjustable weight 44 thereon. It will be observed that this device is similar to the safety-valve of a steam-engine, but that its operation is diverse to the latter device, and in the event that the suction or vacuum force becomes excessive or greater than is desired and which will be regulated by the adjustment of the weight 44 the valve 40 is drawn inwardly to open the seat 39 and to permit

the ingress of air to the cylinder 1, and thereby lessen said suction or vacuum force. In advance of the valve 40 the pipe 38 also has 70 rotatably mounted therein a plug-valve 45, operable by a suitable key or other device and provided with a clack-valve 46 of any suitable design or type, and when properly adjusted so operates as to open toward the 75 cylinder, and beyond the said valve 45 the pipe is continued any suitable distance for attachment to a suitable water-supply for the purpose of cleansing the several parts of the apparatus or machine.

It will be understood that as many cows may be milked at one time with one machine as there are receivers and teat-cups, provided the cylinder 1 has a sufficient capacity and upon which will always depend the number 80 of cows milked. In starting the operation the regulator, heretofore described, should be gaged at about one-third of an atmosphere, more or less, and beyond the number of receivers used the stop-cocks 18 will be closed, 90 and if the vacuum or suction force is too great and painful annoyance is apparent by the effect on the teats of the cows the regulator automatically opens and relieves the injurious pressure effect of the machine under such 95 conditions. The milk is drawn into the receivers as heretofore explained and from thence is forced into the pipe 34, and in preparing the machine for operation the piston 6 is first moved forward to the full limit of 100 its stroke in said direction, and after every part has been applied and adjusted for the milking operation the said piston is gradually drawn rearwardly, the suction or vacuum force set up, and the milk drawn into the receiver, the valve 12 being in the position shown in Fig. 2. On the return forward stroke of the piston pressure is exerted through the flexible conveyer 20 downwardly 105 on the milk in the receiver in each instance 110 and said milk forced outwardly through the conduit 33 and at the same time drawing air inwardly through the vent 37. This operation becomes continuous until the cows are thoroughly milked, when the several receivers will be disconnected and again used in a similar manner, or if in disuse they will be hung up, as shown in Fig. 1. To protect the teat-cups and keep the same clean, a teat-cup cover 47 is employed, which is of such dimensions as to snugly fit over the said teat-cups 115 and are easily removable at any time when it is desired to employ the milking apparatus in the manner just set forth.

If it is desired to cleanse the several parts 120 of the apparatus or machine after milking and which is always necessary to preserve said parts in a pure and sweet condition and prevent souring or stagnation of the deposits that may remain therein, the pipe 38^a is connected to a water-supply source and the valve 130 45 is turned to bring the clack-valve thereof toward the cylinder 1, and the valve 12 is turned to the position shown by Fig. 4 and so

that the clack-valve 15 thereof will open outwardly or away from the direction of the cylinder. The piston is then drawn backwardly in the cylinder 1, which will cause an inflow of water through the pipe 38; but owing to the position of the valve 15 and the operation thereof just stated no exhausting effect will be produced in the apparatus to which the pipe 11 is connected, and on the return stroke 5 or forward movement of the piston 6 the clack-valve 46 in the plug-valve 45 will be forced to close and the similar valve 15 in the plug 12 opened and the water forced through the entire apparatus and out to the pipe 34 and from thence take the same course as the 15 milk and find an outlet through the spout 35. Successive charges of water thrown through the apparatus in the manner set forth will result in great benefit, as will be readily understood, and in forming the several parts of the apparatus care will be taken to utilize such metals or other materials as will withstand corrosion. It is also proposed to use a suitable motive power for the piston and to 20 make such other changes in the form, size, proportions, and minor details as fully fall within the scope of the invention.

Having thus described the invention, what is claimed as new is—

- 30 1. In a milking apparatus operated by suction, the combination of air-exhausting devices, a suction-conveyer connected to said devices, one or more milk-receivers connected to said suction-conveyer and having gravitating valves operating in the lower portions thereof, outflow-conduits connected to the milk-receivers and having air-vents, and a common outflow-pipe for said conduits.
2. In a milking apparatus, the combination 40 of air-exhausting devices having an automatic regulator, one or more milk-receivers having teat-cups, an exhaust-conveyer from said exhaust devices, an outflow-pipe common to all the receivers, and flexible conveyers between each receiver and the exhaust-conveyer and outflow-pipe, the flexible conveyer between the receiver and outflow-pipe having an air-vent and a gravitating valve adjacent the receiver.
- 45 3. In a milking apparatus, the combination 50

of air-exhausting mechanism, a regulator in intimate relation to said mechanism, an exhaust-conveyer attached to said mechanism and having a valve therein with ways therethrough at angles to each other, one or more 55 milk-receivers adapted to be suspended on the cows and having teat-cups upwardly projecting therefrom, a milk-receiving pipe or conveyer to all the receivers, and flexible tube connections between the upper and lower portions of each receiver and the exhaust-conveyer and milk-receiving pipe or conveyer, the said milk-receiver having a gravitating valve operating in relation to its outflow connection and the latter also provided with an 60 air-vent.

4. A washing mechanism for a milking apparatus and permanently forming a part of the latter, comprising a cylinder having an open rear end and a front closed end, a piston movably mounted in said cylinder, a pipe attached to the closed end of the cylinder supplied with a rotatable valve having a way therethrough covered at one end by a clack-valve opening outward from the rotatable 75 valve, the said pipe being connectible to a water-supply, an exhaust-conveyer also attached to the closed end of the cylinder and having a valve therein provided with ways therethrough in planes at right angles to each 80 other, one of the ways having a clack-valve at one extremity opening outward from said valve, the said exhaust-conveyer being continuous at a distance from the exhausting devices and connected to milking apparatus. 85

5. A milking apparatus comprising a milk-receiver having upper and lower connections and upstanding teat-cups, the lower connection adjacent the central bottom portion of the receiver having a gravitating valve therein with a stem provided with upper divergent arms and also supplied with an air-vent, and air-exhausting devices. 90

In testimony that I claim the foregoing as my own I have hereto affixed my signature in 95 the presence of two witnesses.

MARK MASON CONDRON.
